US00D943585S

(12) **United States Design Patent** (10) Patent No.: **US D943,585 S**
 Engineer et al. (45) Date of Patent: **** Feb. 15, 2022**

(54) **DIGITAL DATA RECEIVER**

- (71) Applicant: **Workaround GmbH**, Munich (DE)
 (72) Inventors: **Sean Engineer**, Munich (DE); **Hans Hochkeppel**, Munich (DE)
 (73) Assignee: **WORKAROUND GMBH**, Munich (DE)
 (***) Term: **15 Years**
 (21) Appl. No.: **29/779,610**
 (22) Filed: **Apr. 20, 2021**

Related U.S. Application Data

- (62) Division of application No. 35/508,584, filed on Aug. 14, 2019 (U.S. filing date under 35 U.S.C. 384), and having an international filing date of Aug. 14, 2019, now Pat. No. Des. 922,063.

Primary Examiner — Keli L Hill*(74) Attorney, Agent, or Firm* — Panitch Schwarze Belisario & Nadel LLP(57) **CLAIM**

The ornamental design for a digital data receiver, as shown and described.

DESCRIPTION

FIG. 1 is a top, front and right perspective view of the digital data receiver, in accordance with our design;

FIG. 2 is a top, rear and right perspective view thereof;

FIG. 3 is a top plan view thereof;

FIG. 4 is a bottom plan view thereof;

FIG. 5 is a rear elevational view thereof; and,

FIG. 6 is a right-side elevational view thereof.

The broken lines in the figures are for the purpose of showing environmental structure and form no part of the claimed design.

1 Claim, 6 Drawing Sheets
